UNITED STATES PATENT OFFICE.

THOMAS H. JERVIS, OF EBENSBURG, PENNSYLVANIA.

GRAVITY-BED.

1,111,654.

Specification of Letters Patent. Patented Sept. 22, 1914.

Application filed January 3, 1914. Serial No. 810,203.

To all whom it may concern:

Be it known that I, THOMAS H. JERVIS, a citizen of the United States, residing at Ebensburg, in the county of Cambria and State of Pennsylvania, have invented new and useful Improvements in Gravity-Beds, of which the following is a specification.

The invention relates to beds, and more particularly to the class of gravity beds 10 adapted for either outdoor or indoor sleeping.

The primary object of the invention is the provision of a bed wherein the same can be shifted through an opening in an outer wall 15 separating a room from a porch so that the occupant of the bed can enjoy either outdoor or indoor sleeping.

Another object of the invention is the provision of a bed whereby the occupant can at 20 will pass through an opening in the wall of a sleeping room to the porch or balcony of a building and vice versa without necessitating the occupant leaving the bed to shift the same.

25 A further object of the invention is the provision of a movable bed of this character wherein the occupant can undress and retire in the sleeping room previous to the passing of the bed onto the porch or balcony, thereby 30 obviating the possibility of catching cold resultant from undue exposure while transferring the bed from the interior to the exterior of the building.

A still further object of the invention is 35 the provision of a bed wherein the occupant on retiring can quickly pass from the porch or balcony to the interior of the room without leaving the bed so as to be protected from storm or intense cold.

40 A still further object of the invention is the provision of a bed wherein the same can be moved from the room onto the porch so that the space ordinarily occupied by the bed within the room will be free for other 45 uses, or the said bed can be moved into the room when not occupied so as to protect the covering used thereon from dampness or exposure to the atmosphere during inclement weather.

50 A still further object of the invention is the provision of a bed of this character which is simple in construction, readily and

easily operated for the purposes specified, 55 thoroughly reliable and efficient in its operation, and inexpensive in manufacture.

With these and other objects in view, the invention consists in the construction, combination and arrangement of parts as will be 60 hereinafter fully described, illustrated in the accompanying drawings, and pointed out in the claims hereunto appended.

In the drawings:—Figure 1 is a fragmentary vertical sectional view through a 65 portion of a room and the porch or balcony of a building, showing the bed constructed in accordance with the invention, and in this instance positioned within the room. Fig. 2 is a similar view, showing the bed transferred to the porch or balcony. Fig. 3 is a vertical transverse sectional view at the outer side of the outer wall of the building, looking toward the opening in the said wall, the bed in this instance being positioned in 70 the room. Fig. 4 is a similar view looking toward the head of the bed when projected through the opening onto the porch. Fig. 5 is a sectional view on the line 5—5 of Fig. 4. Fig. 6 is a sectional view on the line 6—6 80 of Fig. 1. Fig. 7 is an enlarged fragmentary sectional view of Fig. 2.

Similar reference characters indicate corresponding parts throughout the several views in the drawings.

85 Referring to the drawings in detail, A designates a portion of a bedroom and B the porch or balcony, both of which are of the ordinary well-known construction. In the dividing wall 10 separating the bedroom A 90 from the porch or balcony B is formed a rectangular-shaped opening 11 having the usual door casement 12 through which is adapted to pass the bed 13 which has its head 14 and foot 15 of the same height with relation 95 to each other, the legs 16 of which have suitably secured thereto wheel forks 17 which are extended through slots 18 arranged in spaced parallel relation to each other and formed in the flooring 19 of the room A and 100 porch or balcony B, the forks 17 being provided with peripherally grooved rollers or wheels 20 which are adapted to travel upon a track structure presently described.

The track structure comprises a pair of 105 guide rails 21 on which travel the rollers or

wheels 20, the said rails being located beneath the flooring 19 in alinement with the slots and are supported upon swinging cranks 22 pivoted thereto at opposite ends 5 of the same and also pivoted in bearings 23 stationarily mounted beneath the flooring 19, the cranks 22 when shifted being designed to tilt the rails 21 in one direction or the other, and this tilting action is accomplished in a manner presently described.

Fixed to the under faces of the rails 21 at an intermediate point thereof are toothed racks 24 which mesh with cog gears 25 fixed to a horizontal shaft 26 journaled in suitable bearings stationarily mounted beneath the floor 19. The shaft 26 underlies the rails 21 and is disposed at right angles thereto to extend crosswise thereof. On one end of the shaft 26 is a beveled pinion 27 with which 15 meshes a beveled gear 28, the same being fixed to the lower end of a driving shaft 29 mounted vertically in bearings 30 fixed within the vertical wall 10 at one side of the opening 11 therein contiguous to the 20 door casement 12, the upper end of the shaft 29 being provided with a beveled pinion 31 which meshes with a corresponding pinion 32 fixed to a hand wheel shaft 33, the ends of which extend beyond opposite faces of 25 the wall 10 and carry hand wheels 34 of the ordinary well-known construction which are in convenient reach of a person occupying the bed when the latter is either positioned within the room A or on the porch or balcony B so that the hand wheel 34 can be rotated for actuating the connections with the rails 21 to tilt the same in a direction to cause the bed to gravitate either from the 30 porch or balcony B into the room A or vice 35 versa.

The inner edge of the door casement 12 has secured thereto a strip 35 which coextends with the same and has fitted in opposite faces resilient strips 36 with which contact the head 14 or foot 15 of the bed when 40 shifted, these strips being designed to act as shock absorbers and also as weather-strips, as either the head or foot serve to close the opening 11 irrespective of the bed 45 being positioned upon the porch or balcony B or within the room A of the building.

A section 37 of the base board is positioned and fixed at the lower end of the opening 11 in the wall 10 so as to serve in 50 closing the space between the legs 16 of the head and foot of the bed when positioned on the porch or balcony or within the room so that this board 37 with the head or foot of the bed will entirely close the opening to 55 exclude drafts of air entering the room through the opening in the wall 10 of the building. It will be noted that the grooves in the peripheries of the rollers or wheels

20 will prevent the same leaving the rails 21 of the track structure when the bed 13 is 55 gravitating in either direction thereon. The angular disposition of the rails 21 when shifted causes the bed 13 to gravitate to the lowermost point of the track structure, thereby running the bed through the opening 11 from the room A to the porch or balcony B or vice versa.

From the foregoing it is thought that the construction and manner of operation of the device will be clearly understood, and therefore a more extended explanation has been omitted.

What is claimed is:—

1. A device of the class described comprising a foundation having elongated slots 80 arranged in spaced parallel relation to each other, intermediate and outer bearings arranged beneath the foundation, cranks journaled in the outer bearings, tracks connected to said cranks for changing the direction of inclination thereof, a shaft journaled in the intermediate bearings and having rack pinions, toothed racks on the track and meshing with the pinions, a movable object supported by said tracks and 85 engaged therewith through the slots, a vertically disposed shaft, gears connecting both shafts, and means for rotating the last-named shaft.

2. A device of the class described comprising a foundation having elongated slots 95 arranged in spaced parallel relation to each other, intermediate and outer bearings arranged beneath the foundation, cranks journaled in the outer bearings, tracks connected 100 to said cranks for changing the direction of inclination thereof, a shaft journaled in the intermediate bearings and having rack pinions, toothed racks on the track and meshing with the pinions, a movable object supported 105 by said tracks and engaged therewith through the slots, a vertically disposed shaft, gears connecting both shafts, means for rotating the last-named shaft, a partition rising from the foundation and having an 110 opening through which the object moves, and means on the object for closing the opening when the same is shifted to either side of the partition.

3. A device of the class described comprising a foundation having elongated slots 115 arranged in spaced parallel relation to each other, intermediate and outer bearings arranged beneath the foundation, cranks journaled in the outer bearings, tracks connected 120 to said cranks for changing the direction of inclination thereof, a shaft journaled in the intermediate bearings and having rack pinions, toothed racks on the track and meshing with the pinions, a movable object supported 125 by said tracks and engaged therewith.

through the slots, a vertically disposed shaft, gears connecting both shafts, means for rotating the last-named shaft, a partition rising from the foundation and having an opening through which the object moves, means on the object for closing the opening when the same is shifted to either side of the partition, and hand operable means connected with the operating means and dis-

posed at opposite sides of the partition and 10 also at one side of the opening therein.

In testimony whereof I affix my signature in presence of two witnesses.

THOMAS H. JERVIS.
